O. E. CLARK

PNEUMATIC HAMMER

Filed June 30, 1924

Patented Oct. 23, 1928.

1,688,449

UNITED STATES PATENT OFFICE.

OMAR E. CLARK, OF DENVER, COLORADO, ASSIGNOR, BY MESNE ASSIGNMENTS, TO THE GARDNER-DENVER COMPANY, OF QUINCY, ILLINOIS, A CORPORATION OF DELAWARE.

PNEUMATIC HAMMER.

Application filed June 30, 1924 Serial No. 723,363.

The present invention relates to that type of motive fluid operated tool in which the supply of air or other expansive motive fluid is controlled by the piston.

5. The object is to provide means whereby the stroke of the piston is materially extended.

The present embodiment is of the type disclosed in Patents Nos. 1,314,288 and 10 1,314,246, both of August 26, 1919.

In these prior tools it has been found that the piston does not closely approach the back head in its rearward stroke, and seemingly the cause of this is due to the fact that the 15 effective area of the front face of the piston being considerably less than that of the rear face and the volume of air admitted to the front end of the piston chamber being relatively small, and furthermore as the front 20 live air port of the hammer remains open only for a short portion of the forward and rear strokes, sufficient pressure is not built up in the front end of the cylinder to carry the hammer by expansion and momentum throughout the full rear stroke. This 25 probably is due to the fact that very early in the rear stroke live air is admitted to the rear end of the piston chamber, and this acting on practically the entire diameter of 30 the piston, stops the hammer early in the stroke. To remedy this and permit a substantially full rear stroke the following mechanism has been provided.

In the drawings:

35 Figure 1 is a longitudinal sectional view through a rock drill equipped with the invention,

Figures 2 and 3 are detail longitudinal views through the valve chamber, illustrating 40 the valve in its two extreme positions,

Figure 4 is a cross sectional view taken on the line 4—4 of Figure 1.

A cylinder member is employed, comprising a barrel or body 5, having a piston chamber 6, in which is slidably mounted a reciprocating piston 7. The rear end of the piston chamber is enlarged, as illustrated at 8. A lubricant reservoir 9 is located against the rear end of the barrel, and abutted against 45 the rear side of this lubricator is the integral flange 10 of a motive fluid supply tube 11, hereinafter more fully described. This flange 10 is clamped against the reservoir by a rear head plate 12.

The piston 7 is provided with an internal 55 constant pressure chamber 13, having a reduced bore 14 at its rear end in which the front end of the supply tube 11 is slidably engaged, said tube constituting means for conveying fluid under pressure to the chamber 13 and maintaining the supply therein. The tube 11 is supplied from any suitable source, preferably through a channel 15 in the back head 12.

For the purpose of distributing the fluid 60 under pressure from the chamber 13 to opposite faces of the piston, forwardly inclined ports 16 open from the front portion of the chamber 13 through the side walls of the piston, and the other ends of these ports are 65 movable into and out of communication with pockets or enlargements 17 formed in the front portions of the cylinder walls. Rearwardly extending ports 18 open from the 70 rear portion of the constant pressure chamber 13 through the side walls of the piston, and these ports are movable into and out of communication with the enlargement 8 of the piston chamber 6. Front and rear exhaust ports indicated at 19 and 20 and overrun by the piston serve to alternately afford 75 communication between the front and rear portions of the piston chamber and atmosphere.

If fluid under pressure is supplied to the 80 internal pressure chamber 13, it will be evident that with the piston in the position shown in Figure 1, this fluid will escape through the ports 16 and pocket 17 into the front end of the piston chamber, while the 85 rear port 20 will be uncovered, allowing the exhaust from the rear end of said piston chamber. Consequently the piston will be driven rearwardly until the ports 18 are uncovered, whereupon the exhaust port 20 will be closed, the outlet port 16 will also be closed, and the exhaust port 19 will be 90 uncovered to allow the exhaust of motive fluid that is in front of the piston. The supply of motive fluid through the ports 18 will operate against the rear end of the piston and drive it forwardly.

The front face 21 of the piston is of much 95 less area than the rear face 22, and it will be obvious that as soon as the ports 16 are closed during the rearward movement of the piston, which closing will take place shortly after the piston begins such rearward move-

ment, then the remainder of the rearward movement must be under the expansion of the air in the front end of the piston chamber. As soon as the ports 18 uncover, however, a volume of live air is immediately delivered into the rear end of the piston chamber and acting on the relatively great surface 22 quickly overcomes the weakening pressure against the smaller front face 21. As a consequence the piston may not secure its full rearward stroke, thus cutting down the efficiency of the tool.

To overcome this, the following mechanism is employed. Formed on one side of the barrel 5 is a valve casing 23 having a longitudinal valve chamber 24. An annular groove 25, formed in the peripheral wall of the chamber 24, has communication by means of an outlet port 26 with one of the pockets 17 or in other words, with the front end of the piston chamber. In rear of the groove 25 is another groove 27, into which opens an inlet port 28 leading from an intermediate portion of the piston chamber 6 and so arranged that it will be traversed by one of the outlet ports 16 in the piston 7. It may be explained at this point that the piston 7, as clearly shown in Figure 4, is held against rotary movement by suitable keys 7^a engaged in keyways 7^b formed in opposite sides of the piston. The front end of the valve chamber 24 has an annular groove 29, from which opens an exhaust port 30. Finally a passageway 31 leads from the enlargement 8 of the piston chamber 6 to the rear end of the valve chamber 24.

In the valve chamber 24 is located a spool valve 32 having a central peripheral groove 33. The valve is adapted to reciprocate and the limit of its forward movement is determined by a plug 34, constituting a closure for the front end of the valve chamber. A supply port 35 opens from the front end of the piston chamber into the front end of the valve chamber at one side of the plug 34 and in advance of the spool valve 32.

The operation of this mechanism is as follows: Assuming the piston in the position shown in Figure 1, its rearward movement will take place, as above described, and the ports 16 will be cut off primarily by passing from communication with the pockets 17. When the piston is in this position the valve 32 will be in its rearward position, as shown in Figure 1, due to the fact that live air from the front end of the piston chamber will pass through the port 35 to the front end of the valve chamber and shift the valve rearwardly, the rear end of the valve chamber, being open through the passageway 31 to the rear end of the piston chamber, and thence to atmosphere through the exhaust port 20. During the rearward movement of the piston, the upper port 16 will however traverse the port 28, and consequently live air can

flow through said port 28 through grooves 27, 33 and 25, and thence through the outlet port 26 into the front of the piston chamber, supplying additional live air and thus insuring a more complete rearward movement of the piston. This operation is indicated in Figure 3. When the port 16 has passed the port 28, the exhaust port 19 will be uncovered to the front end of the piston, while the supply ports 18 will open into the enlargement 8. When this takes place, the piston starts on its forward movement, and at the same time motive fluid delivered into the enlargement 8, will find its way through the passageway 31 and operate against the rear end of the valve 32, while pressure against the front end of said valve is reduced because the port 35 is now open through the front end of the piston chamber to the exhaust port 19. The valve will thereupon shift to the position shown in Figure 2. Consequently grooves 25 and 27 will be cut off from communication with each other and ports 26 and 28 will be correspondingly cut off. The port 28 being thus closed, the port 16 will pass it without releasing any air from the chamber 13, but the port 26 will now be in communication with the exhaust port 30, as a consequence of which the closing of the exhaust port 19 by the advancing piston will still leave a supplemental exhaust through the port 30, allowing the piston to move forward without material resistance so that it will deliver a more powerful blow.

From the foregoing, it is thought that the construction, operation and many advantages of the herein described invention will be apparent to those skilled in the art, without further description, and it will be understood that various changes in the size, shape, proportion and minor details of construction, may be resorted to without departing from the spirit or sacrificing any of the advantages of the invention.

What I claim, is:—

1. In a motor of the character described, the combination with a cylinder member having a piston chamber and a piston therein having an internal motive fluid supply chamber, of means for maintaining fluid under pressure in said chamber, said piston having spaced outlet ports from the chamber that alternately deliver fluid to the piston chamber on opposite sides of the piston and said ports being controlled by portions of the cylinder member, a supplemental passageway for motive fluid in the cylinder member having a port traversed by an outlet port of the piston, said supplemental passageway having an outlet port opening into the piston chamber on one side of the piston, and an exhaust port, and an automatic valve alternately opening an outlet port and exhaust port.

2. In a motor of the character described,

the combination with a cylinder member having a piston chamber and a piston therein having an internal motive fluid supply chamber, of means for maintaining fluid under pressure in said chamber, said piston having spaced outlet ports from the chamber that alternately deliver fluid to the piston chamber on opposite sides of the piston and said ports being controlled by portions 5 of the cylinder member, a valve chamber having an inlet port opening into the piston chamber and traversed by an outlet port of the piston, an outlet port opening into the piston chamber in front of the piston 10 and an exhaust port, an automatic valve in the valve chamber movable to a position to afford communication between the inlet and outlet ports of the valve chamber and to another position to cut off such communication 15 and afford communication between the outlet port and the exhaust port, and a passageway leading from the rear end of the piston chamber to the valve chamber to supply motive fluid to the latter for shifting 20 the valve.

3. In a motor of the character described, the combination with a cylinder member having a piston chamber provided with terminal pockets, of a piston operating in the piston chamber and having an internal fluid chamber and spaced outlet ports extending from the fluid chamber and alternately moving into communication with the pockets, means for supplying motive fluid to the internal chamber, and a supplemental passageway in the cylinder member opening into one of the pockets and having an inlet end traversed by the outlet port of the piston that moves into communication with said pocket, a main exhaust port from the cylinder covered and uncovered by the piston, a supplemental exhaust port opening from the same end of the piston chamber as that having the pocket to which the supplemental passageway leads, and an automatic valve 35 controlling the supplemental passageway and supplemental exhaust.

In testimony whereof, I affix my signature.

OMAR E. CLARK.
